UNITED STATES PATENT OFFICE.

RALPH S. DAVIS, OF KNOXVILLE, TENNESSEE.

LAMP.

Application filed April 27, 1926. Serial No. 104,988.

This invention relates to lamps, and more particularly to portable reading lamps which are attachable to various articles of furniture.

5 It has heretofore been proposed to provide such lamps with reflectors which have been placed on one side of the lamp so as to intercept the rays directed to that side and reflect them back toward the other side 10 of the lamp. Such reflectors, however, diffuse the light rays throughout a large zone and do not reflect a beam directly on the reading matter to be illuminated. Moreover, the direct rays of the lamp are combined with the reflected rays in the light 15 zone. This is particularly objectionable when the lamp is attached to a bed, for example, and is directly above the head of the reader, since the light rays strike directly 20 into the eyes, resulting in a glare annoying to the reader and injurious to the eyes.

One object of the present invention is to provide a novel and improved form of reading lamp which may be adjusted to effectually 25 prevent the light rays from striking the eyes of the reader and at the same time to properly illuminate the desired object.

Another object is to provide a lamp with a reflector which may be adjusted to throw 30 a beam of light which is restricted to the reading matter or other object.

A further object is to provide means in a reading lamp whereby the direct rays are 35 intercepted and reflected rays only are directed onto the reading matter, thus producing an indirect lighting effect.

Two embodiments of the invention have been illustrated in the accompanying drawings, but it is to be expressly understood 40 that these drawings are for purposes of illustration only and are not to be taken as a definition of the limits of the invention, reference being had to the appended claims for this purpose.

45 In the drawings—

Fig. 1 is an elevation in section of one embodiment of the invention;

Fig. 2 is a plan view of Fig. 1, the cover or "shade" being removed for the sake of 50 clearness; and

Fig. 3 is an elevation in section showing another form of glare shield.

Referring now to Figs. 1 and 2 which 55 illustrates one embodiment of the invention, 1 indicates a supporting frame of any suitable type, which as here shown comprises a

wire framework. A suitable covering 2, of cloth or other material, partially surrounds the circumference and ends of the frame 1, an opening for the passage of light rays being left in a portion of the circumference, which opening, as shown in Fig. 1, is in the lower side of the frame 1. Suitable means are provided for attaching the frame 1 to an article of furniture, such as the head-board 3 of a bed. In the form shown, the frame 1 is provided with two rearwardly extending arms 4 adjacent its upper portion, the outer ends of said arms being curved downwardly to engage the head-board of 70 the bed, and with a rearwardly extending wire bracket 5 adjacent its lower portion, which rests against the head-board 3.

At one end of the frame, an electric light socket 6 is mounted by means of a wire bracket 7, and carries an electric lamp 8.

Light rays from the lamp 9 can escape from the device only through the opening in the lower side of the cover. To prevent the direct rays from passing through this opening and striking the eyes of the reader, suitable means, preferably adjustable, are provided for closing said opening to any desired extent, said means comprising an adjustable shade or glare shield, 9, made of cloth or other suitable material. One end 10 of the shade 9 is preferably secured to the cover 2 at one side of said opening. Said shade passes over a supporting rod 11, suitably attached to the frame 1, adjacent the end 10, and is provided with a plurality of transversely extending rod members 12, spaced throughout its length. The ends of the rod members 12 are supported in suitable guideways 13, formed on the frame 1, or attached thereto in any suitable manner, and preferably comprising a pair of substantially parallel spaced wires between which the ends of the rod members 12 slide. Rods 12 have enlargements on their ends to retain them in the guideways. By sliding the rod 12, the shade 9 may be adjusted to close said opening to the desired extent.

A reflector 15, of glass, metal or other suitable material, is mounted on a bracket 16 pivotally secured to the frame 1 by pivot pin 17, in a position to receive the rays of light from the lamp and reflect the same through the opening in the cover. Preferably, the mirror is mounted at the rear edge of said opening, in a substantially vertical position and extending partially within the

framework 1, and has a resilient member 18 attached to its rear side and passing around the bracket 16, serving to strengthen the support of the mirror and to exert a slight tension on the pivotal mounting, so that the mirror will retain its position.

In Fig. 1, the glare shield 9 is shown extended to its full length and the mirror adjusted to a vertical position. The rays of light extending directly downward from the lamp are interrupted by the shield 9, but the rays extending rearwardly and downwardly pass over the glare shield 9 and strike the mirror 15, which reflects them forwardly and downwardly under the glare shield 9, the direction and size of the reflected light beam being shown in dotted lines. By adjusting the mirror 15, as shown in dotted lines in Fig. 1, the direction of this beam of light may be varied.

Fig. 3 illustrates another form of glare shield which may be employed. In this embodiment the glare shield is wound on a roller 19 suitably mounted at each of its ends in the frame 1. A small chain or wire 20 is wound around the roller 19 and attached to the latter, the free end of said wire being attached to a resilient member, such as the spring 21, said spring being attached to the frame 1. The spring 21 is adapted to rotate the roller 19 so as to wind up the shade 9. The slide 13 is provided with a series of notches 22 in which the ends of the rod member 12 engage, so as to maintain the shade in the desired position. For convenience in adjusting the shade, a small handle 23, preferably of wire, is attached to the rod 12.

It will be seen that the direct rays from the electric light cannot escape from a reading lamp constructed according to the invention and that the reflected rays only are directed outwardly for illuminating purposes. All annoying and injurious glare is therefore eliminated. At the same time the beam of reflected light may be adjusted in any desired direction, and is restricted to the object to be illuminated.

While two embodiments of the invention

have been illustrated in the accompanying drawings, it is to be expressly understood that the invention is not limited to these embodiments, but is susceptible of a variety of expressions, and that changes may be made in the construction and arrangement of parts without departing from the spirit of the invention. Reference is therefore to be had to the appended claims for a definition of the limits of the invention.

What is claimed is:—

1. In a device of the class described, a frame, a cover for the upper and side portions of said frame, an electric lamp supported within said frame, a horizontally adjustable shield partially closing the lower portion of said frame, and a reflector pivoted on said frame below and to the rear of said lamp, said reflector being adapted to direct light from said lamp forwardly and downwardly under said shield.

2. In a device of the class described, a frame, an electric lamp mounted on said frame, an adjustable shade below said lamp, means for mounting said shade including a roller and resilient means normally tending to wind up said shade on said roller, means maintaining said shade in an adjusted position, and a reflecting mirror pivoted to said frame below and to the rear of said lamp.

3. An indirect lighting bed lamp comprising a lamp, an opaque cover therefor extending around and under said lamp and having an opening restricted to the part thereof which is to the rear of and in a substantially horizontal plane below said lamp, said cover intercepting all rays from said lamp except through said opening, and a substantially vertical reflector positioned in the rear part of said opening and extending partially above said plane within the cover and partially below said plane, said reflector receiving rays directed toward said opening and reflecting a beam of light outwardly of said cover and forwardly and downwardly.

In testimony whereof I have signed this specification.

RALPH S. DAVIS.
